STEAM PRESSING IRON AND STEAM-SUPPLY MECHANISM THEREFOR

Alfred E. Reimers, Clearbrook, and Walter K. Tavender and Leonard J. McCormack, Jr., Winchester, Va., assignors to Reimers Electric Appliance Co., Inc., Clearbrook, Va., a corporation of New York

Application September 13, 1954, Serial No. 455,511

5 Claims. (Cl. 38—77)

This invention relates to improvements in electrically or gas heated steam pressing irons and steam-supply mechanism therefor.

Electrically heated steam irons during a pressing operation thereof discharge steam which is supplied thereto through a steam hose, pipe or like conduit from a suitable steam-supply source. Such irons are highly efficient when being so used and the steam in the supply conduit is flowing. Difficulty is met, however, when the iron is used only intermittently with periods of non-use or idling. For example, when an iron is thus idling and left on the stand with the supply valve closed and with steam pressure in the supply hose while no steam is flowing through the discharge apertures of the iron, there is a continuous accumulating condensation of steam in the supply hose. This is due to constant loss of heat and the cooling effect of the atmosphere on the hose and adjacent parts will continue to cause condensation during the idling period. This condensed steam will collect at the valve of the iron until the steam supply hose or conduit becomes filled or partially filled with water. Under such circumstances, when, in order to utilize the iron in another operation, the valve on the iron is opened to supply and discharge steam, the water condensed in the hose from the steam supply and gathered adjacent to the valve will be initially supplied to the iron and while some of such water will be immediately turned into steam in most cases there will be a surplus of such water above the quantity which can be turned into steam in the iron and this surplus will cool the iron and cause a water spotting to result during such operation of the iron.

It is desirable in electrically heated steam pressing irons to utilize an iron which discharges a large amount of steam. This is desirable for most industrial operations and requires a large flow through the iron and through the supply hose or conduit, and when such large discharge irons are used there is consequently greater condensation when the iron is idling or not in use with the valve closed.

In accordance with our invention, we prevent the accumulation of condensation of steam by the use of means for continuously draining water as the same is condensed from steam in the steam supply hose or conduit and this continuous draining is accomplished through a bleeding connection with the steam supply at or near the iron or adjacent to the inlet valve of the steam iron, and in the preferred form of our invention such bleeding of the steam supply in the supply hose or conduit carries out of the steam supply hose a small amount of live steam with the condensed steam and we preferably combine with bleeding means a means for carrying the steam and water off through a supplemental tube or hose into a suitable waste receptacle. The operation of bleeding the steam supply is thus carried on outside the iron and condensation of steam into water in the supply hose which is the feeding means to the iron is avoided and conse-

2

quently does not interfere with the pressing temperature nor with the temperature of the steam discharged.

Another object of our invention is to utilize in a steam-supply metallic connection to the iron having a conventional steam-supply passage a metallic bleeder member comprising a metallic tube having a small diameter bore or hole preferably leading from the steam-supply passage to atmospheric pressure. This small bore or hole is of a diameter that is less than .040" and is less than 16% of the steam passage which it bleeds and is preferably produced by utilizing in the side of the metallic steam-supply connection a relief tube member of suitable metal which is provided with such a small diameter hole.

15 We have found that by continuously draining or bleeding to the atmosphere a very small amount of water of condensation from the supply-hose connection or through the supply valve at the iron, and preferably through a metallic relief tube, the condensation of steam within the supply-hose is prevented from accumulating and this small amount of draining or bleeding does not in any way affect the temperature of the sole plate of the iron because upon the opening of the supply valve to discharge steam through the iron no rush of water enters the iron, 20 but on the contrary the use of this draining or bleeding element will enable a perfectly dry steam to be produced even when the iron is heated to the low temperature of approximately 225° F. It is understood that other means are utilized to avoid condensation, as, for example, the 25 "cracking" or leaving partly open of the supply-valve, but this expedient permits escape of too much steam and is not practical because it is frequently forgotten by the operator; also evaporation inside the iron has been employed but a high degree of heat which would be at least 300° F. and sometimes as much as 400° F. would be necessary in order to enable a quick drying of the 30 condensed steam within the hose and thus to avoid water spotting during an operation.

With these and other objects in view, the invention 40 comprises the combination of members and arrangement of parts so combined as to coact and cooperate with each other in the performance of the functions and the accomplishment of the results herein contemplated, and comprises in one of its adaptations the species or preferred 45 form illustrated in the accompanying drawings, in which:

Fig. 1 is a view of an electrically heated steam pressing iron embodying my invention and having a steam-supply valve and a steam supply connection;

Fig. 2 is a section through a metallic connection between 50 the supply hose and iron and showing our tubular bleeder member connected thereto as an independent fitting to such steam supply connection from which steam is passed to the valve of the iron; and

Fig. 3 is a cross-section of the tubular bleeder member 55 removed from the supply-hose connection and showing the bore therethrough of small diameter.

Referring now to these drawings which illustrate a preferred embodiment of my invention, 10 is a conventional electrically heated steam pressing iron which is preferably 60 of the type shown in patents to Walter K. Tavender, numbered 1,874,832 and 1,911,213 and embodies a suitable steam passage 11 that supplies steam to the other passages of the iron 10 not shown. In the embodiment of our invention shown, a flexible steam supply-hose 12 of standard form which is connected at its receiving end to any suitable source of steam supply, not shown, is connected at its discharge end 12a to a metallic connection member 13, which, as illustrated, is independent of the operating valve for the iron. As shown in the instant embodiment of our invention, the connection 13 is connected to a metallic pipe 13a suitably mounted on the 65

iron and having its bore connected with passage 14 leading to the lead-passage 15 of the iron 10 which is provided with valve seat 15^c controlled by valve stem 15^a operated by a handle 15^b pivoted intermediate its ends at 15^c and connected at 15^d to valve stem 15^a, said handle having its outer manipulating end extending freely above the body of the valve and iron and spaced therefrom. The valve stem 15^a is normally retained in closed position by a spring 15^e extending between the valve body and said handle 15^b. As shown, the valve stem 15^a is seated on valve seat 15^c positioned intermediate the conduits 14 and 15, and, when the valve stem is raised, steam will be admitted to the conduit 15 and thence to the steam discharge passages 24 from which steam is discharged through the sole plate portion 10^a of the iron 10.

It will be understood, as hereinabove stated, that in devices of this character steam which is supplied through the standard hose 12 condenses in connection 13 and hose 12 and a considerable amount of water may thus, unless regulated as hereinafter stated, be gathered in said hose 12. Such a gathering of water will occur when there is a relatively long period of idling of the iron and thereupon, when the valve 15 is opened, such condensed water will pass into the passages and at normal temperatures of the pressing iron will not be all converted into steam, and consequently if and when the iron is used after an idling period, water spotting of the material being ironed will result.

In accordance with our invention, accumulation of the condensation of water in the steam supply at the metallic connection 13 and the adjacent portion of the hose 12 is prevented, and in the preferred embodiment of our invention we provide a metallic bleeder tube or fitting having a small bore which is connected with the steam supply passage through the metallic connection 13. This connection 13 has a steam passage 16 and screw threads 17 and 18 at opposite ends for connection with the iron and with the metallic connecting member 12^a of the supply hose 12, and in the embodiment illustrated, we provide said metallic connection 13 intermediate the ends thereof with a screw-threaded bore 19 extending from the steam passage 16 to the outside surface thereof and insert into said metallic connecting member 13 a screw-threaded metallic bleeder tube 20 which is provided with a small bore 20^a adapted to continuously bleed or permit the passage therethrough from the connection 13 and tube 12 of a very small amount of steam, which small amount of steam we have found to be sufficient to carry with it any condensation which would otherwise occur within the hose 12 and metallic connection 13.

In the embodiment illustrated, we have embodied in the metallic bleeder tube 20 a small bore or hole 20^a of only .020" diameter and we preferably connect integrally with said tube 20 an elbow portion 21 which is provided with a somewhat enlarged bore 21^a, and said elbow portion 21 of said bleeder tube 19 is preferably connected to a rubber bleeder tube 22 which preferably extends in the same direction as the supply tube or hose and has a container 23 arranged beneath the end thereof for the purpose of catching and containing water which drips from said rubber tube 22.

In the embodiment shown, the metallic bleeder tube 19 comprises part of the tube 21 which is preferably formed of brass and has a relatively small outside diameter of say one-eighth of an inch and is connected to the small rubber tube 22 by simply slipping said rubber tube over the elbow portion of the metallic bleeder tube 21 for the purpose of leading water with some steam which is continuously blown out of the connection 13 and which is, as above indicated, passed through the elbow portion 21 of the bleeder tube member and its rubber lead tube 22 to the atmosphere or to a suitable water-drip container 23.

It will be understood, of course, that the bleeding of the steam supply might be accomplished in the passage

14 or in any suitable position in a steam supply passage where steam condensation accumulates.

In the preferred form of our invention illustrated, the hose connection 13 is, as above indicated, provided at 5 opposite ends with screw-threads 17—18 so as to permit connection at one end to the metallic pipe 13^a and at the other end to a suitable connection 12^a of the hose 12 and is provided intermediate its ends with a screw threaded bore 19^a into which the screw threaded end 19 10 of the metallic bleeder member or tube is inserted.

It will be understood that this bleeder member construction completely eliminates the accumulation of condensed water in the tube 12 and connection 13 and also that the small flexible bleeder tube does not in any way 15 interfere with the proper operation of the iron. Furthermore, said flexible lead tube 22 may, if desired, be suitably connected to the supply tube 12 so as to be carried therewith during operation of the iron.

As hereinabove stated the bore or hole 21 of the metallic bleeder tube 20 is .020" in diameter and this small bore comprises a very small percentage, viz. eight (8) percent of the diameter of the steam passage or bore 16 through the supply connecting fitting 13 with which it is connected. Such bleeding, therefore, does not in its function 25 of preventing condensation and spotting deleteriously affect the efficiency of the steam supply to the iron nor the economy of operation thereof.

The bleeding operation works at substantially atmospheric pressure. There is some back pressure due to 30 the moving of water up through the outlet tube 22, and the discharge end of this tube 22 may, if desired, be immersed in water in the pail 23. The difference in pressure is the force which drains the water away from the iron and moves the same into the pail 23. We have 35 found that the use of a bleeding bore 20^a of larger diameter than .040" is impractical because it would be too wasteful of steam, and a bore of less than .020" diameter would not provide a sufficient degree of bleeding to be practical.

40 Having described our invention, we claim:

1. A steam pressing iron and steam supply mechanism therefor comprising, in combination, an electrically-heated pressing iron provided with discharge passages for discharging during a pressing operation steam supplied 45 from a suitable source of steam supply, a steam supply conduit comprising a flexible tube connected at one end with said source of steam supply and having its opposite end connected to and movable with the pressing iron during operation thereof, a steam-receiving passage in 50 the pressing iron having a connection with the movable end of said flexible tube to receive and conduct to the discharge passages of said pressing iron steam received from said flexible tube, a supply-controlling valve in said iron arranged between said steam-receiving passage and said steam discharge passages, and steam-bleeding means 55 located adjacent to the connection of the movable end of said steam supply conduit with said steam-receiving passage in the iron for continuously bleeding a small portion of the steam being fed through the steam-supply 60 passage of said steam-supply conduit to prevent accumulation of condensation thereof in said movable end of said steam-supply conduit.

2. A steam pressing iron and steam supply mechanism 65 therefor as claimed in claim 1 in which the valve-controlled steam supply conduit which comprises a flexible tube having one end movable with the pressing iron and provided at said movable end with a metallic connection member movable with and connecting said flexible tube to said steam-receiving passage of the pressing iron, said metallic connection member having a main steam-supply passage of relatively large diameter communicating with the steam-supply passage of said flexible steam-supply conduit, and said metallic connecting member 70 also having a secondary bleeding passage of small diameter communicating with said main supply passage for 75

bleeding steam passing through the end of the steam-supply passage connected with the pressing iron to prevent the accumulation of condensed steam within said steam-supply conduit.

3. A steam pressing iron as claimed in claim 1 in which the steam-supply conduit is valve controlled by valve of the pressing iron and includes a flexible tube and is provided with a metallic connection member movable with and connecting said flexible tube with said steam-receiving passage of the pressing iron, said metallic connection member having a steam-supply passage communicating with the steam-supply passage of said steam-supply conduit, a steam bleeding metallic fitting member is provided and mounted in said metallic connection member for bleeding the steam-supply through the passage therein, said metallic fitting member extending transversely through said metallic connection member and provided with a bore contacting at one end with the steam passage therein and at the opposite end being connected with the outer atmosphere.

4. A steam pressing iron and steam supply mechanism therefor comprising, in combination, an electrically-heated pressing iron provided with discharge passages for discharging during a pressing operation steam supplied from a suitable source of steam supply, a steam-supply conduit including a flexible tube connected at one end with said source of steam supply and having its opposite end connected to and movable with the pressing iron during operation thereof, a steam-receiving passage in the pressing iron having a connection with the movable end of said flexible tube to receive and conduct to the discharge passages of said pressing iron steam received

from said flexible tube, a supply-controlling valve in said pressing iron arranged between said steam-receiving passage and said steam discharge passages, and steam-bleeding means located adjacent to the connection of the movable end of said steam-supply conduit with said steam-receiving passage in the pressing iron for continuously bleeding a small portion of the steam being fed through the steam-supply passage of said steam-supply conduit to prevent accumulation of condensation thereof in said steam-supply conduit, said steam-bleeding means comprising a metallic connection member having an axial steam-supply passage and provided at its opposite ends with screw-threaded connections to the flexible conduit and to the pressing iron, said metallic connection member being provided intermediate said ends with a metallic fitting element having a small bore between .020" in diameter and .040" connected with the steam passage through said connection member for continuously bleeding a small amount of steam from said steam-supply passage and passing the same to the atmosphere.

5. A steam pressing iron and steam supply mechanism therefor as claimed in claim 4 in which the metallic fitting element has at the inlet end thereof a small bore of approximately .020" in diameter and a larger bore at the outlet end and a flexible hose is connected to the fitting element at the outlet end thereof and extends to a water-drip container.
